By Spear, Middlem, Donaldson, *Atty.*

UNITED STATES PATENT OFFICE.

HANS GRADE, OF BORK, GERMANY.

PUNCH.

Application filed February 6, 1923. Serial No. 617,824.

To all whom it may concern:

Be it known that I, HANS GRADE, citizen of the Republic of Germany, residing at Bork, i./M., Germany, have invented certain 5 new and useful Improvements in Punches, of which the following is a specification.

The invention relates to the construction of the cutting edges of punch heads for the stamping of sheet metal. The new embodiment of the cutting surfaces serves to increase the efficiency of the punch, i. e., to increase the total cutting surface and lessen the amount of power required. In general, a plane cutting surface is employed which 15 simultaneously penetrates through the material upon the whole cutting line. Hand punches are known with one pre-cutting section. Punch heads are also known with several pre-cutting sections and one-sidedly arched 20 ranged cutting surfaces, whereby the pre-cutting section runs into a sharp point. In the case of the new embodiment of the cutting surfaces the cut commences at two or more definite points, and upon further operation the penetration extends symmetrically along the whole cutting line. This cutting line may be either straight or curved.

In the drawing the embodiment of the punch head is diagrammatically shown, in 30 which—

Figs. 1-3 illustrate details of a round punch;

Figs. 4-6 details of a square punch.

With the round punch the cutting edge 35 lies upon a cylindrical surface, so that the cutting line Fig. 2 appears in the development.

When punching, the points 1 contact first with the blank, and finally the points 2. 40 In the case of the square punch according to Fig. 4 all four cutting edges are rounded off so that the points 3 contact with the blank first, and finally the points 4. The cutting line proceeds from 1 and 3 respectively in symmetrical manner in order to prevent displacement of the material. An obtuse angle, as shown in dotted lines in Fig. 45 4, may be employed for the cutting edges in-

stead of the curved embodiment. The difference between the highest and lowest points 50 of the cutting line must be greater in accordance with the strength of the material to be cut. If, for example, a punch as maximum accomplishment stamps through 3 mm. sheet metal, by increasing the difference between the highest and lowest points of the cutting line by 3 mm., 6 mm. metal may be stamped. The loud noise otherwise customary with punching, produced by the tension of the material, is eliminated. In the case 60 of larger punches with complicated cutting it is absolutely necessary to commence with the cutting at several points, and if possible in the manner that the entering points are divided uniformly on the circumference. 65 In this way the bending of the punch is prevented, and at the same time the material is held firmly at several points and cannot be displaced.

The dotted lines in Fig. 4 illustrate a 70 square punch in which the edges of its working face are not arcs, but are composed of straight lines which form angles.

What I claim is:—

1. In combination, a punch, working with 75 in an aperture, said punch having a cutting edge coextensive with its periphery, the working face of the punch including this cutting edge, said edge having a portion adapted to first engage the work and de- 80 form it into the punch aperture.

2. In combination, a punch, a die having an aperture therein, said punch having a cutting edge, said edge entering said aperture at two points simultaneously, said entering 85 action proceeding symmetrically away from each entering point.

3. A punch having a working face, a cutting edge on said punch coextensive with the face periphery, said face being a part of a 90 cylindrical surface.

In testimony whereof I have affixed my signature in the presence of a witness.

HANS GRADE.
